UNITED STATES PATENT OFFICE.

HIGINIO CANUDAS, OF MEXICO, MEXICO.

COMBINED BOOK-HOLDER AND PORTFOLIO.

SPECIFICATION forming part of Letters Patent No. 245,347, dated August 9, 1881.

Application filed June 22, 1881. (No model.)

To all whom it may concern:

Be it known that I, HIGINIO CANUDAS, of the city of Mexico, Republic of Mexico, have invented certain new and useful Improvements in Combined Book-Holder, Portfolio, and Slate, of which the following is a specification.

The object of this invention is to provide a cheap and simple device for carrying books, papers, pencils, pens, &c.

In the accompanying drawings, forming a part of the specification, Figure 1 is a perspective view of the front of my device; Fig. 2, a back view, and Fig. 3 a section of same.

Similar letters of reference refer to similar parts in the several figures.

The invention consists in the construction of a frame-work sustaining a revolving handle at the top to tighten a strap or cord designed to clamp the books or papers to be carried. Between and incorporated into the frame is arranged a receptacle formed by the ends B, slate S forming the back and cross-piece D.

In my drawings, A represents the revolving handle, and B the ends of the frame, which unite with bottom C and cross-piece D, which form a receptacle covered upon the back or rear side by a slate, S, and upon the front side by a door, E, fastened at the top by slide-bolt 30 F, and secured at the bottom by hinges G G. The end pieces, B, project above the cross-piece D, and form supports for the ends of the revolving handle A and the pawl-and-ratchet mechanism. Within this receptacle may be carried papers, pencils, pens, and other small articles.

Books to be carried are held by the straps or cords H H, which cords H are attached to the cross-piece D of the frame, pass through

the eyes J J, and over the revolving handle A, the said handle being provided with a ratchet-wheel, K, and pawl L, by which device the slack of the strap or cord is taken up and held as the handle is revolved. To liberate this fastening a thumb-plate, M, is provided at the point shown, or some other convenient point, whereby the operator can, by pressing thereon quickly, release the books or other articles from the strain of the cords or straps H H.

It may be here stated that other means may be employed for taking up the slack of said cord or strap or for fastening the revolving handle A than that described.

What I claim as my invention, and desire to secure by Letters Patent of the United States, is—

1. A portfolio consisting of a rectangular receptacle, as described, provided with a hinged-door and a cord secured to the back of the receptacle and passing around the door to a revolving handle having a pawl-and-ratchet mechanism, whereby the cord may be tightened or loosened, substantially as and for the purpose set forth.

2. In a portfolio and book-holder, the combination, with cross-piece D, bottom C, and end pieces, B, forming a rectangular receptacle, said end pieces projecting above cross-piece D and supporting a revolving handle and pawl-and-ratchet mechanism, of a slate, S, forming the back or rear of the receptacle, and a door, E, held by a cord, H, substantially as described.

HIGINIO CANUDAS.
